INVENTOR:
HOLTON VICE,

By
Ford W. Harris

ATTORNEY.

UNITED STATES PATENT OFFICE

HOLTON VICE, OF LOS ANGELES, CALIFORNIA, ASSIGNOR OF ONE-FOURTH TO CECILE ARNOLD, OF LOS ANGELES, CALIFORNIA

ADJUSTABLE HINGE

Application filed March 2, 1932. Serial No. 596,242.

My invention relates to hinges, and relates particularly to a hinge having a simple eccentric hinge pin structure by which the plates of the hinge may be relatively adjusted.

An object of my invention is to provide a hinge which may be adjusted to properly position a door within an opening, or a swinging member relative to another swinging member, and which can be adjusted at any time to compensate for shrinkage and swelling of doors, to prevent them from binding at the jamb or in the casing in which they are hung. Where a door has been improperly set or has swollen or shrunk so that it binds or is too loose in its casing or is set too close to the jamb, it is necessary either to plane off part of the door or the casing or reset the hinges. This consumes more or less time and is accordingly relatively expensive. My invention makes it possible to quickly adjust a door to proper position in a casing without removing the door from its hinges or marring the paint or finished surfaces of either the door or the casing, as occurs where it is necessary to reset hinges, or plane off a part of the door or the casing.

It is a further object of my invention to provide a simple eccentric hinge pin for hinges which may be cheaply manufactured and easily installed, and which will give entirely satisfactory service.

It is a further object of the invention to provide a hinge pin construction comprising a pintle adapted to pass through pintle openings in hinge plates and eccentric members mounted on the pintle.

A further object of the invention is to provide a hinge pin construction of the above character in which the eccentric members comprise longitudinally slotted cylindrical members.

Further objects and advantages of the invention will be brought out in the following part of the specification.

Referring to the drawing which is for illustrative purposes only,

Fig. 1 is a sectioned face view of a hinge embodying my invention.

Fig. 2 is a cross-section on a plane represented by the line 2—2 of Fig. 1.

Fig. 3 is a cross-section on a plane represented by the line 3—3.

Fig. 4 is a perspective view of the hinge pin structure showing the eccentrics placed thereon.

Fig. 5 is a perspective view of one of the eccentrics.

My invention is adapted for use with various types of hinges such as butts employed for hinging doors. The form of the invention shown in the drawing comprises a hinge 11 having cooperating hinge plates 12 and 13, the plate 12 having three pintle journals 14 providing openings 15, and the plate 13 having journals 16 which extend into the spaces 17 between the journals 14 and having openings 18 therein. Through the openings 15 and 18 a hinge pin structure 20 is extended, this hinge pin structure, as best shown in Fig. 4, comprising a bar or pintle 21, the lower portion 22 of which is of non-circular cross-section so that such lower portion 22 when resting in slots 24 formed in eccentrics 25 will not rotate in such slots but will cause the eccentrics 25 to remain in relatively stationary positions on the pintle 21. The lower deformed or non-circular portion 22 of the pintle 21 is cheaply and easily formed by flattening the lower portion of a round pintle by removing metal from opposite sides thereof, so that two opposite flat faces 27 will be provided on the lower portion 22 of the pintle 21, which flat faces will rest between the parallel faces 28 of the groove or slot 24 in the eccentric 25.

The eccentric 25 consists of cylindrical bodies, a pair of which employed in a hinge, such as shown in the drawing, consists of a cylindrical body having a longitudinal slot or groove which may be formed therein in various manners as by milling around the bar or cylindrical body. The slot 24 in the eccentric 25 is of such size that it will fully receive the cross-sectional area of the lower portion 22 of the pintle 21. The openings 15 in the journals 14 are of a diameter to relatively closely fit the pintle 21, and the openings 18 are of a diameter to receive the

eccentrics 25. The eccentrics 25 are made preferably the same length as the journals 16, as shown in Fig. 1, and are placed in the openings 18 before the journals 16 are moved 5 into the notches 17 between the journals 14. The pintle 21 of the pin structure 20 is passed through the openings of the journals 14 and 15 and through the slots or grooves 24 of the eccentrics 25. On the lower threaded end 30 of the pintle 21 a cap 31 is screwed, which, after adjustment of the pin structure to desired position, may be tightened so as to bind the pintle 21 against rotation, thereby holding the pin structure 20 against rotative 15 movement relative to the plate 12.

My simple adjustable hinge may be readily made from standard hinges and butts procurable on the market. To install the eccentric pin structure 20 all that is necessary is to 20 separate the hinge plates and ream out the journals of one of the plates to larger diameter to receive the eccentrics 25.

Although I have herein shown and described my invention in simple and practical 25 form, it is recognized that certain parts or elements thereof are representative of other parts, elements, or mechanisms which may be used in substantially the same manner to accomplish substantially the same results; 30 therefore, it is to be understood that the invention is not to be limited to the details disclosed herein but is to be accorded the full scope of the following claims.

I claim as my invention:

35 1. An adjustable hinge device of the character described, including: a pair of members adapted to be pivotally secured together in primary and secondary relationship, said members having cooperating journals through which a pin structure may be extended; and a pin structure extended through 40 said journals, comprising a pintle having a cylindrical eccentric means thereon provided with an open longitudinal slot along one side thereof adapted to receive said pintle.

50 2. An adjustable hinge device of the character described, including: a pair of members adapted to be pivotally secured together in primary and secondary relationship, said members having cooperating journals through which a pin structure may be extended; and a pin structure extended through 55 said journals, comprising a pintle having eccentric means thereon consisting of a cylindrical member having an open longitudinal slot along one side thereof to receive said pintle, said cylindrical member being in non-rotative engagement with said pintle.

60 3. An adjustable hinge device of the character described, including: a pair of members adapted to be pivotally secured together in primary and secondary relationship, said members having cooperating journals through which a pin structure may be extended; and a pin structure extended through 65

said journals, comprising a pintle having eccentric means thereon consisting of a cylindrical member having a longitudinal groove along one side thereof through which said pintle extends, said groove being of non-circular cross-section, and said pintle being of non-circular cross-section at its point of engagement with said groove to prevent relative rotation of said eccentric means and said pintle. 75

4. An adjustable hinge device of the character described, including: a pair of members adapted to be pivotally secured together in primary and secondary relationship, said members having cooperating journals through which a pin structure may be extended; and a pin structure extended through 80 said journals, comprising a pintle having eccentric means thereon consisting of a cylindrical member having a longitudinal groove along one side thereof through which said pintle extends and held in position on said pintle by journals of the hinge device, said groove being of non-circular cross-section, and said pintle being of non-circular cross-section at its point of engagement with said groove to prevent relative rotation of said eccentric means and said pintle. 85 90

5. An adjustable hinge device of the character described, including: a pair of members 95 adapted to be pivotally secured together in primary and secondary relationship, said members having cooperating journals through which a pin structure may be extended; and a pin structure extended through 100 said journals, comprising a pintle having eccentric means thereon consisting of a cylindrical body having a longitudinal groove along one side thereof of substantially rectangular cross-section adapted to receive said 105 pintle, said pintle being flattened on opposite sides so as to fit said groove of said eccentric means.

6. An adjustable hinge device of the character described, including: a pair of members 110 adapted to be pivotally secured together in primary and secondary relationship, said members having cooperating journals through which a pin structure may be extended, the openings of the journals of said primary member being of relatively small diameter and the openings of the journals of said secondary member being of relatively large diameter; and a pin structure extended 115 through said journals comprising a pintle of 120 diameter to fit said small openings and having eccentric means thereon comprising a cylindrical body having a longitudinal groove therein to receive said pintle in said large openings, said eccentric means being held in 125 place on said pintle by said journals of said secondary member, said groove being of non-circular cross-section and said pintle being flattened to fit into said groove in a non-rotary relation. 130

7. An eccentric pin structure of the character described for use in a hinge structure, including: a pintle; and an eccentric member of cylindrical form having a longitudinal groove in the external cylindrical face thereof to receive a portion of said pintle.

8. An eccentric pin structure of the character described for use in a hinge structure, including: a pintle having a portion of non-circular cross-section; and an eccentric member of cylindrical form having a longitudinal groove in the external cylindrical face thereof to engage said portion of said pintle in non-rotary relation.

15 9. An eccentric pin structure of the character described for use in a hinge structure, including: a pintle having a portion of flattened cross-section; and an eccentric member of cylindrical form having a longitudinal groove of rectangular cross section in the external cylindrical face thereof to fit said portion of said pintle in non-rotary relation.

20 10. An eccentric pin structure of the character described, for use in a hinge having a pintle member, comprising a cylindrical body having an external longitudinal groove along the side thereof of a size to receive a portion of said pintle member.

25 11. An eccentric pin structure of the character described, for use in a hinge having a pintle member with a portion of non-circular cross section, comprising a cylindrical body having an external longitudinal groove along the cylindrical face thereof to engage 30 said portion of said pintle member in non-rotary relationship.

35 In testimony whereof, I have hereunto set my hand at Los Angeles, California, this 26th day of February, 1932.
